ALBERT K. McMURRAY, OF UTICA, NEW YORK.

Letters Patent No. 91,469, dated June 15, 1869.

IMPROVED ROCKING-CHAIR.

The Schedule referred to in these Letters Patent and making part of the same.

To all whom it may concern:

Be it known that I, ALBERT K. McMURRAY, of Utica, New York, have invented new and useful Improvements in Rocking-Chairs; and I do hereby declare that the following is a full, clear, and exact description of my said improvement, and of the mode of operation of the same, reference being had to the annexed drawing, making a part of this specification, in which—

Figure 1 is a perspective view of the rocking-chair.
Figure 2, a side view of the rocking part.

The seat and upper parts of the chair may be of almost any form.

I attach, to the under side of the seat, two rockers, A A, and a base for the chair is formed, supported on legs, with casters, if desired, having two rockers, similar to A A, but with the rocking edges turned up, or the reverse of A A, on which A A rest.

A steel spring, D, lies between each pair of upper and lower rockers, A and B, and is attached firmly to the front end of the lower rocker, or B, and to the rear end of the upper one, or A, as seen in the drawings.

In front of the chair, I put a small stool or foot-support, hinged to the frame, so as to be let down for use, or turned up, to be out of the way, at pleasure.

This foot-rest is so arranged, that when turned up, the front edge of the seat will rest upon it, and the

chair will be thereby prevented from rocking forward, and will be changed from a rocking to a common chair.

The operation of my improved rocking-chair will be obvious from the description given.

The springs D D, arranged as described, aid in giving motion to the chair, and also serve to keep the seat upon the base.

The side covers C C also serve to keep the parts in place.

By using reverse rockers, in the manner described, an easy and large motion is obtained, and there is no necessity of extending the rockers behind the chair; and, when not desired to be used for rocking, it serves all the purposes of a commodious arm-chair.

Having thus described my invention,

What I claim as new, and desire to secure by Letters Patent, is—

The combination and arrangement of the reverse rockers A and B, the springs D D, and the part E, when the latter is arranged to turn down for use as a footstool, or to turn up, and form a rest for the front edge of the chair-seat, and prevent the same from rocking, substantially as and for the purposes herein specified.

ALBERT K. McMURRAY.
